8 Claims. (Cl. 52-2)

1

This invention relates to an improvement in delay electric blasting caps, and more particularly to new delay compositions for use therein.

Delay electric blasting caps as used in present practice comprise essentially an ignition charge, a detonating charge and a delay element through the medium of which the detonating charge is fired. The delay element is customarily a fuse of such length and composition as will afford the desired delay interval between firing of the ignition and detonating charges.

Compositions heretofore used in delay elements are, for example, mixtures of barium peroxide, selenium metal powder and talc, or potassium permanganate and antimony metal powder, either one of which compositions in burning produces very little gas on combustion and hence may be used in ventless delay caps.

Black powder, either compressed in a carrier or spun in a fuse which is then sized into a metal carrier and cut into appropriate lengths, has also been used as a delay composition. However, due to the large volume of gases evolved in combustion of black powder, the cap casing must in this instance be provided with a vent to permit the free escape of gases which, if not thus released, would cause irregularities in the burning rate of the delay composition with consequent defects in the order of firing of a series of such caps. The vent in the cap casing is usually sealed with a rupturable membrane to prevent entrance of moisture. In such caps there is a tendency toward overlapping due to the effect of back pressure on the rate of burning of the delay composition. Also, because of the open vent there is a frequent occurrence of misfires in wet ground due to shock from previous blasts.

In either vented or ventless delay electric blasting caps, the delay compositions as used in the prior art burn at a rate of several seconds per inch of length, the desired delay periods being obtained by increasing the length of the delay element and hence, as the delay periods become longer, the length of the cap is increased to the point where it becomes inconvenient to handle in priming explosive charges.

An object of our invention is therefore a new and improved ventless delay electric blasting cap assembly containing a delay composition the combustion of which results in much shorter delay periods than heretofore obtainable. A further object of our invention is the provision of novel delay compositions which burn at such high temperatures that there is no possibility of misfires due to failure of the delay composition after ignition. A still further object is the provision of a short period delay electric blasting cap, the use of which results in considerable reduction in ground vibrations which is an important factor in quarrying operations. Additional objects of our invention will become apparent as the description proceeds.

2

The foregoing objects may be accomplished by the use of a delay element and means of ignition such as are used in a normal type of ventless delay electric blasting cap assembly, the delay composition and means of ignition being designed to function in such a way that the delay intervals obtained in rotational firing of the caps of our invention are in the order of milliseconds. The delay composition is a fast and hot burning relatively gasless mixture which is obtained by the use of mischmetal or an alloy of mischmetal combined with suitable oxidizing agents and a fuel.

Our invention may be understood more readily by reference to the accompanying drawing which serves to illustrate the invention in its preferred form.

Figure 1 shows a longitudinal sectional view of a delay electric blasting cap in which 1 is a solid drawn cylindrical metal shell in the base of which is pressed a suitable charge of detonating explosive such for example as tetryl or pentaerythritoltetranitrate 2. Directly above the base charge 2 is pressed a suitable priming charge 3 on top of which is pressed a delay element 4 containing the delay composition 5. The priming charge 3 may for example be a mixture of lead azide and lead styphnate or the like, while the delay element 4 comprises a lead tube into which is pressed the delay composition 5. Arranged at a distance above the delay element 4 is shown the ignition means which comprises a low tension relatively gasless matchhead assembly 6 to which are attached two insulated cap wires 8 held in position by means of a sulphur plug 9 on top of which is an asphaltic waterproofing 10. The whole ignition means is positioned at the desired distance from the delay element 4 by means of two indent 11 in the shell 1 which act as a stop for the sulphur plug 9.

The delay composition 5 is preferably a homogeneous mixture of mischmetal alloyed with magnesium or aluminium to which is added a fuel such as silicon and an oxidizing agent such as red lead. This delay composition being essentially gasless there is no necessity for providing vents in the blasting cap illustrated in Figure 1.

The term "mischmetal" as used above and throughout the remainder of the specification and the claims refers to the commercially available alloy of rare earth metals having the following approximate analysis:

	Per cent
55 Cerium	49.0
Lanthanum	25.6
Neodymium	16.0
Praseodymium	4.6
Samarium	2.0
60 Terbium	1.0
Yttrium	1.0
Iron	0.8

Our invention is more specifically illustrated by reference to the following examples in which the delay element used in each instance had the following general dimensions, viz. length 0.300 inch, outside diameter 0.257 inch and inside diameter 0.090 inch. The delay element was prepared by tamping the loose delay composition into a large diameter lead tube which was subsequently sized down by rolling or drawing to the correct diameter followed by cutting the element from the sized tube to the length specified above. In each instance the delay composition was prepared by grinding the mischmetal or alloy of mischmetal with another metal followed by sieving through a 325 mesh sieve having an opening of 0.0017 inch. Fuels such as silicon were treated in a like manner while the oxidizing agents were ground to pass a 200 mesh standard screen sieve having an opening of 0.0029 inch. The various components of the delay composition were then blended in a tumbling barrel until the mixture became homogeneous.

Example 1

Using a standard blasting cap assembly as heretofore described, the following table is illustrative of the burning characteristics of the various mischmetal/metal alloys or mixtures which may be used in the delay compositions of our invention. In conjunction with the mischmetal/metal alloy or mixture we have found it preferable to use a fuel such as silicon, and we prefer to use red lead as a source of oxygen in the proportions shown in the table.

TABLE

Mischmetal/Metal Alloy	Silicon	Red Lead	Burning Time
Percent	Percent	Percent	Milli-seconds
70/30 Mischmetal/Al	13.4	24.1	62.5
70/30 Mischmetal/Mg	13.4	24.1	62.5
70/30 Mischmetal/Ni	13.4	24.1	62.5
70/30 Mischmetal/Zn	13.4	24.1	62.5
70/30 Mischmetal/Co	13.4	24.1	62.5
70/30 Mischmetal/Si	13.4	24.1	62.5
70/30 Mischmetal/Te	13.4	24.1	62.5
70/30 Mischmetal/Cu	13.4	24.1	62.5
70/30 Mischmetal/Se	13.4	24.1	62.5
70/30 Mischmetal/Sb	13.4	24.1	62.5
70/30 Mischmetal/Fe	13.4	24.1	62.5
70/30 Mischmetal/Pb	13.4	24.1	62.5
70/30 Mischmetal/Mn	13.4	24.1	62.5
70/30 Mischmetal/Sn	13.4	24.1	62.5

Example 2

Using the standard blasting cap assembly as heretofore described, the following table is illustrative of the change in burning characteristics obtained in the delay compositions when the ratio of mischmetal to metal in the alloy or mixture is altered, other conditions remaining the same. The choice of magnesium as an alloying ingredient is merely illustrative of the general effect of altering the composition of the alloy or mixture.

TABLE

Mischmetal/Metal Alloy	Silicon	Red Lead	Burning Time
Percent	Percent	Percent	Milli-seconds
100/0 Mischmetal/Mg	13.4	24.1	62.5
80/20 Mischmetal/Mg	13.4	24.1	62.5
70/30 Mischmetal/Mg	13.4	24.1	62.5
60/40 Mischmetal/Mg	13.4	24.1	62.5
50/60 Mischmetal/Mg	13.4	24.1	62.5
40/60 Mischmetal/Mg	13.4	24.1	62.5
30/70 Mischmetal/Mg	13.4	24.1	62.5
0/100 Mischmetal/Mg	13.4	24.1	62.5

Example 3

Using the standard blasting cap assembly as heretofore described, the following table is illustrative of the change in burning characteristics obtained in the delay composition using different oxidizing agents. In obtaining this comparison the various oxidizing agents used were proportioned so that, based on the most likely end product of combustion, an equivalent amount of oxygen was made available as compared with an amount utilized in the formulations disclosed for the previous examples. The 70/30 mischmetal/magnesium alloy was used as a basis for this comparison and silicon for the fuel.

TABLE

70/30 Mischmetal/Mg Alloy	Silicon	Oxidant	Burning Time
Per cent	Per cent	Per cent	Milli-seconds
13.4	24.1	Pb ₃ O ₄	62.5
15.6	23.0	PbO ₂	56.4
25.1	45.1	KMnO ₄	29.8
18.7	33.6	BaO ₂	47.7
24.3	43.6	Ba(NO ₃) ₂	32.1
26.2	46.8	KClO ₄	27.0
19.1	34.3	PbCrO ₄	46.6
24.7	44.5	KClO ₃	30.8
24.4	43.8	MnO ₂	31.8

30

Example 4

Using the standard blasting cap assembly as heretofore described the following table is illustrative of the change in burning characteristics obtained when an inert diluent is added to a delay composition comprising:

Per cent
70/30 Mischmetal/Aluminum Alloy
Silicon
Red Lead

40
45
50

The diluent chosen was bentonite, a hydrated aluminium silicate having the general characteristics desired of a diluent for a combustible mechanical mixture.

Table

Composition	Bentonite	Burning Time
Per cent	Per cent	Milli-seconds
100	0	17
95	5	23
90	10	63
85	15	85
80	20	154

Example 5

Using the standard blasting cap assembly as heretofore described the following table is illustrative of a series of short period delays which may be obtained when using the relay compositions of our invention and varying the length of the delay element. The compositions disclosed were selected with a view to demonstrating a series of short period delays having 25 millisecond intervals between period means, and were also selected with a view to obtaining as short an overall cap length as possible in order to facilitate manufacture and handling.

TABLE

Period No.	Delay Composition			Element Length	Delay Interval
	Mischmetal/Metal Alloy	Silicon	Oxidant		
1	20/80 Mischmetal/Mg.	14.9	26.9	Per cent	Per cent
2	30/70 Mischmetal/Si.	13.4	24.1	<chem>Pb3O4</chem>	43.2
3	70/30 Mischmetal/Mg.	13.4	24.1	<chem>PbCrO4</chem>	15.0
4	50/50 Mischmetal/Mg.	3.7	24.1	<chem>Pb3O4</chem>	62.5
5	30/70 Mischmetal/Mg.	10.7	24.1	<chem>Pb3O4</chem>	62.5
6	70/30 Mischmetal/Mg.	13.4	24.1	<chem>Pb3O4</chem>	0.30
7	50/50 Mischmetal/Mg.	3.7	24.1	<chem>Pb3O4</chem>	0.50
8	30/70 Mischmetal/Mg.	10.7	24.1	<chem>Ba(NO3)2</chem>	32.1
9	50/50 Mischmetal/Mg.	15.2	27.3	<chem>Pb3O4</chem>	61.5
10	50/50 Mischmetal/Mg.	3.7	24.1	<chem>PbCrO4</chem>	46.6
11	30/70 Mischmetal/Mg.	10.7	24.1	<chem>Ba(NO3)2</chem>	32.1
12	50/50 Mischmetal/Mg.	15.2	27.3	<chem>PbO2</chem>	43.0
13	50/50 Mischmetal/Mg.	22.1	39.7	<chem>PbCrO4</chem>	14.5
14	50/50 Mischmetal/Mg.	15.2	27.3	<chem>PbO2</chem>	24.1
15	50/50 Mischmetal/Mg.	15.2	27.3	<chem>PbO2</chem>	14.1
				<chem>PbCrO4</chem>	43.0
				<chem>PbCrO4</chem>	14.5

While the above may be taken as an embodiment in its preferred form of a complete series of short period delays having intervals between period means of 25 milliseconds, it is apparent to those skilled in the art that other complete series having any other desired intervals between period means such as 50 milliseconds, 75 millisecond or higher may be obtained by selecting the various ingredients and/or adjusting the length of the delay element.

The delay compositions of our invention are particularly advantageous in that on burning, substantially no gas is produced and hence they can be used in a ventless delay electric blasting cap assembly with the attendant advantages of this type of cap. A further advantage of our invention lies in the fact that the compositions disclosed burn at high temperatures and thus are not subject to variation in rate of burning due to varying temperature conditions encountered in mining operations. A still further advantage of our invention resides in the fact that the duration of the delay interval can be readily varied to give any desired interval in the range of times considered most desirable for short period delay electric blasting caps.

Obviously the number of combinations of mischmetal alloy, fuel, oxidizing agent and diluent that can be selected to give the desired burning rate for short period delay intervals is almost infinite and any desired combination can be obtained by a proper selection of ingredients for the delay composition.

It is to be understood that the details disclosed in this specification are for the purpose of illustration only and that the invention is not to be limited to the specific disclosures but may be modified and embodied in various other forms without departing from its intended scope.

We intend to be limited only by the following claims:

We claim:

1. A delay composition for delay electric blasting caps which comprises between 24% and 47% of silicon, between 32% and 63% of an oxidizing agent and mischmetal alloyed with a metallic element consisting of aluminium, magnesium, nickel, zinc, cobalt, silicon, tellurium, copper, selenium, antimony, iron, lead, manganese and tin.

2. A delay composition for delay electric blasting caps which comprises between 24% and 47% of silicon, between 32% and 63% of an oxidizing agent, and between 13% and 26% of an alloy of mischmetal with magnesium.

3. A delay composition for delay electric blasting caps which comprises between 24% and 47% of silicon, between 13% and 26% of an alloy of mischmetal with magnesium and between 32%

35 and 63% of an oxidizing agent from the group consisting of red lead, lead dioxide, potassium permanganate, barium peroxide, barium nitrate, potassium perchlorate, potassium chlorate, lead chromate and manganese dioxide.

40 4. A delay composition for delay electric blasting caps which comprises silicon 24.1%, an alloy of mischmetal with magnesium 13.4%-14.1% and red lead 61.5%-62.5%.

45 5. A delay composition for delay electric blasting caps which comprises silicon 43.6, an alloy of mischmetal with magnesium 24.3% and barium nitrate 32.1%.

50 6. A delay composition for delay electric blasting caps which comprises silicon 33.6%, an alloy of mischmetal with magnesium 18.7% and barium peroxide 47.7%.

7. In a delay electric blasting cap, a delay composition which comprises 24.1% by weight of silicon, 13.4% by weight of an alloy of mischmetal with aluminum and 62.5% by weight of red lead.

55 8. In a delay electric blasting cap, a delay composition which comprises 24.1% by weight of silicon, 13.4% by weight of an alloy of mischmetal with silicon and 62.5% by weight of red lead.
